WRENCH

August C. Ertner, Seattle, Wash., assignor to Federal Trading Co., Seattle, Wash., a partnership composed of August C. Ertner and J. Frank Thorn

Application October 2, 1943, Serial No. 504,727

2 Claims. (Cl. 81—152)

My invention relates to a quick adjustable wrench, and more specifically to the particular type of jaw holding mechanism employed.

While my wrench jaw holding mechanism may be incorporated in wrenches of different types, in any such installation the user may merely push the movable jaw towards the fixed jaw, thus to grip the work between them, without directly manipulating the jaw holding mechanism. The movable jaw will be held automatically in such work gripping position against great force tending to separate the jaws. Despite ability of the jaw latch to resist displacement of the movable jaw under working load such jaw can be released by a simple manual operation for movement away from the fixed jaw.

It is therefore an object of my invention to provide jaw latching mechanism which will be moved automatically into holding position whatever the spacing between the jaws may be, so that it will be in condition at all times to resist movement of the movable jaw away from the fixed jaw by a force reacting between them. Nevertheless the movable jaw may be quickly retracted at will from the fixed jaw, and over any distance, by manually releasing the latch mechanism.

More specifically it is an object to provide a latch construction capable of affording such operation without being injured by a heavy load which can be withstood by the other wrench parts, and without slippage of the movable jaw upon initial application of the load. The latching mechanism is therefore positive and self-acting.

An additional object is to provide a latching wrench having such capabilities but composed of few parts, which can be produced by simple machine operations, and which can be assembled readily to afford an economical, yet an efficient and convenient tool.

Other objects of my invention which result from the particular nature and characteristics of the mechanism which I prefer will be understood from the following detailed description of a wrench construction typical of my invention. It will be understood that the wrench shown in the drawing is only representative, being one type in which my latch can be used, and various details of the latch construction can be altered as desired while embodying the important features defined more particularly in the appended claims.

Figure 1 is a top perspective view of a wrench

embodiment my latch, with parts broken away to reveal the latch structure.

Figure 2 is a side elevation view of the wrench head, with part of the casing broken away to expose internal structure, and Figure 3 is a rear elevational view of the wrench head.

Figure 4 is a plan view of a latch plate removed from the wrench. Figure 5 is a perspective view of one type of latch spring which may be employed.

As a typical embodiment of my invention I have illustrated in the drawing a monkey wrench including a fixed jaw 1 integral with a rectangular shank 10, which shank projects through an aperture 20 in a movable jaw 2, guided by the shank for reciprocation toward and away from the fixed jaw 1. The end of the shank remote from the fixed jaw forms the handle. It will be understood that the particular shape of the jaws 1 and 2, the manner in which the jaw 1 is mounted on its shank 10, and the angular relationship of the jaws to the shank are matters of choice, and may be varied according to the particular type of wrench embodying my latch mechanism, and the use for which the wrench is intended. The latch construction described below is interengaged between the movable jaw 2 and the shank 10, irrespective of the particular jaw structure features and the extent of movement of jaw 2 along the shank 10.

The latch construction, to which my invention particularly relates, is enclosed within a case 3, preferably made of sheet metal, which may be secured to the lower portion of the movable jaw 2 in any suitable manner, such as by a screw 30. It will be understood that the aperture in the bottom of this casing through which the shank 10 projects, and the hole 20 in the movable jaw itself, are of a size to afford sufficient clearance for the shank to slide easily through them without binding. Neither the movable jaw nor the case is relied upon to assist in gripping the shank for the purpose of holding the movable jaw from sliding along the shank.

The latch mechanism proper consists of a plurality of thin plates 31, at least two in number, each having a body portion of a size approaching the inner cross section of the casing 3. Each latch plate embraces shank 10 somewhat loosely, for example the shank may project through a hole 32 which is of a width just sufficient to slip easily over it, but of an extent in the direction of the plate length appreciably exceeding the width of the shank parallel to the jaws 1 and 2, so that such plates may tilt at a substantial an-

gle relative to the shank. Moreover aperture 32 is preferably located considerably nearer one end of the plate 31 than the other, to form a tongue projecting transversely of the wrench shank for a substantial distance beneath movable jaw 2. The tongue of the upper plate 31 abuts the bottom of a shoulder 21 projecting from a portion of jaw 2 remote from the wrench shank 10 downward well below the portion thereof through which the shank passes. Such shoulder is inclined relative to the shank so that its portion most remote from the shank projects farthest downward, as will be discussed more fully hereafter.

Because aperture 32 in each plate 31 is longer than the corresponding transverse dimension of the wrench shank, each latch plate may tilt through a substantial angle relative to the shank to pinch it between the lower corner of the aperture edge at the base of the latch plate's tongue and the upper corner of the opposite aperture edge. The several plates, arranged in superposed registry, as shown in the drawing, will be tilted conjointly by a force reacting between the jaws. As the force is applied the sliding jaw will tend to move away from the fixed jaw, that is downward in Figure 2, and the jaw shoulder 21 will press against the outer end of the tongue of the upper latch plate 31 at a location substantially beneath the center of the gripping part of jaw 2 projecting beyond shank 10. Such pressure will tilt the upper latch plate by the leverage thus exerted, and in succession each latch plate beneath it, in a direction so that the lower corner of the aperture edge next to the tongue and the upper corner of the aperture edge remote from the tongue will bite simultaneously against the shank.

Assuming that the apertures 32 in all the overlapping latch plates 31 are of the same length, the corresponding corners of all the apertures will thus bite similarly against shank 10 simultaneously, as shown in Figure 2. Even though the latch plates may be rather thin and may tend to be bent by the force exerted on their tongues by the jaw shoulder, any deflection which occurs will act to increase the gripping effect of each plate upon the shank. No individual latch plate can be deformed beyond its elastic limit, however, because each plate in turn supports the one above it, and all therefore act in concert to withstand the stress exerted on them by pressure of the jaw shoulder 21.

It is to be noted particularly how the pressure of the jaw shoulder against the tongue of the upper latch plate is transmitted successively to each of the underlying latch plates. All these latch plates abut contiguously, and preferably the holes 32 of all the plates are of precisely the same length. If there is any variation in the length of such holes the hole in each underlying plate should not exceed the length of the hole in the plate next above it. Only where the plates are of sufficiently thin stock to be somewhat yieldable under loads usually to be expected, a slight variation may not be too detrimental. In that event, the plates all being in contiguous face-to-face engagement, the tongue of each under plate would bend slightly before the plate next above it would grip the shank.

In order to insure substantially immediate gripping of all the latch plates against shank 10 a spring 33, encircling the shank, is interposed between the bottom of the case 3 and the apertured end of the lower latch plate. The specific shape of such spring is not of great importance, but

that shown in Figure 5 has been found to be effective and is very compact. This spring, of the compression type, acts against the apertured ends of the latch plates in a direction toward fixed jaw 1 to tilt the latch plates about shoulder 21 as a fulcrum, that is, in the same direction as pressure by the jaw shoulder tends to tilt the plates relative to shank 10. Thus upon application of a force reacting between the jaws the latch plates will merely be forced more tightly against the shank, already being located properly lengthwise of the shank to exert the requisite holding action. The only separating movement of the jaws which can occur under load, therefore, is that corresponding to the deflection of the tongues of the plates.

In order to exert the maximum leverage action on the latch plates for their length it is desirable that the jaw shoulder 21 engage the tongue of the upper plate at a considerable distance from shank 10. Anticipating the possibility of some slight deflection of the latch plates under heavy load, the lower end of the jaw shoulder is preferably inclined relative to shank 10 at an angle somewhat greater than the maximum angle at which the latch plate tongues can be tilted when the plates are in gripping attitude. The shoulder thus engages the upper plate tongue at all times substantially along a line immediately below the central portion of the part of jaw 2 projecting beyond shank 10, to leave clearance between such tongue and the portion of the jaw shoulder nearer shank 10 under all loading conditions.

Since tilting of the latch plates 31 to decrease the angle between them and shank 10 accomplishes a gripping action to restrain sliding of the movable jaw along the shank, it will be evident that the latch plates may be released from the shank, to enable the movable jaw to be slid along it, by tilting them in the opposite direction. Such movement increases the angle between the latch plates and the shank, moving them into a position more nearly perpendicular to the shank so that clearance is afforded between the latch plate apertures and the shank.

Such latch releasing tilt of the latch plates may be accomplished positively by engagement of the operator's thumb with a tab 34 projecting from the end of the upper latch plate 31 opposite the latch plate tongue. As shown in Figures 2 and 3, this tab projects through a slot in the back of the casing, so that it may be engaged readily. Preferably all the plates have such tabs, so that the releasing pressure is transmitted from one plate to the next at a location reasonably far from the slide. It is not necessary, however, that more than the uppermost plate have such a tab. If the lowermost plate also has a similar tab 34, however, it may serve as a seat for a rearwardly projecting loop of spring 33, as shown.

The operation of my wrench will be readily apparent. The movable jaw may simply be pushed toward the fixed jaw, during which operation the latch plates will slide along the shank, since there is no load on them. In fact, if the tongue of the lower latch plate is engaged by the case 3, the plates would all be tilted positively toward released position, more nearly perpendicular to the shank. Nevertheless whenever the movable jaw comes to rest spring 33 will immediately push the latch plates away from the bottom of the case, so that the tongue of the upper latch plate will be pressed against shoulder 21, and the plates will be tilted substantially into shank gripping

position. When the load is applied on the wrench, therefore, creating a force tending to separate the jaws, the pressure of shoulder 21 on the upper latch plate, transmitted in turn to the underlying latch plate, will tend to tilt them relative to shank 10 in a direction to grip it tightly.

Because the latch plates are in contiguous face-to-face contact, each one supports the other over substantially its entire area to afford an intimate, distributed supporting action. Even though each plate is made of material so thin that the force exerted by jaw shoulder 21 would readily bend it, if used alone, the stacked arrangement of the latch plates, in which they act conjointly, will prevent deflection of any plate to an extent which would result in its permanent deformation or breakage. Furthermore, while a single latch plate would not afford sufficient gripping action because only two corners would be pressed against the shank, where a plurality of latch plates are provided two corners of each exert a gripping force, so that even with two plates a satisfactory holding action is effected, which a single latch plate will not produce. Each additional plate will add two more gripping edges, but two or three plates will usually afford all the holding action necessary.

As long as any substantial load is applied between the jaws the latch plates will be pressed against the shank too tightly for them to be released even by pressure of the thumb on the upper latch plate tab 34. The leverage of the jaw shoulder 21 on the latch plate tongues is considerably greater than that afforded by pressure on the plate tabs. The gripping action of the latch plates therefore cannot be inadvertently released, even if the wrench is being manipulated by two hands.

When pressure on the movable jaw is relieved, however, pressure on the latch plate tabs 34 will tilt the plates readily into released position, because of the considerable leverage offered by such tabs. The movable jaw may then be slid readily away from or toward the fixed jaw to any extent desired. Although it is not necessary in most instances to apply manual pressure to the latch plate tabs in order to release the plates positively for closing movement of the jaws, such reciprocation may be facilitated in some instances by such manipulation, especially immediately after the wrench has been subjected to an unusually great load which tends to set the latch plates tightly against the shank.

It will be seen, therefore, that with my latch construction the wrench may be operated readily for either opening or closing movement of the jaws by one hand, and the desired jaw movement may be accomplished very quickly. Despite such ease of adjustment the provision of a plurality of contiguously engaged latch plates produces an immediate and sufficiently powerful gripping action to prevent any appreciable slippage of the movable jaw upon application of a load or there-

after, however great such load may be within the capacity of the wrench as a whole.

I claim as my invention:

1. A wrench comprising a fixed jaw, a shank integral with said fixed jaw and projecting generally transversely therefrom, a movable jaw slideable on said shank and having a shoulder projecting from the side thereof opposite said fixed jaw and located remote from said shank, the end of said shoulder being inclined toward said shank and fixed jaw, and a plurality of thin latch plates disposed in contiguous face-to-face contact, apertured to embrace said shank and engaging said movable jaw shoulder, being tilttable by pressure of said shoulder thereon, by a force acting to separate said jaws, into pinching engagement with said shank at an angle relative thereto slightly greater than the angle of inclination of said shoulder end relative to said shank, to preserve line contact between said plate and the side of said jaw shoulder farthest from said shank under usual loads, thereby restraining sliding of said movable jaw along said shank away from said fixed jaw, said latch plate being engageable with an appreciable area of said fixed jaw shoulder upon bending under excessive loads, such engagement limiting the degree of possible bending of said plate.
2. A wrench comprising a fixed jaw, a substantially rectangular shank integral with said fixed jaw and projecting generally transversely therefrom, a movable jaw slideable on said shank and having a shoulder projecting from the side thereof opposite said fixed jaw and located approximately at the center of its gripping part projecting from said shank, the end of said shoulder being inclined toward said shank and fixed jaw, a plurality of thin latch plates disposed in contiguous face-to-face contact and having a substantially rectangular aperture therein to embrace said shank, each having a tongue projecting a substantial distance transversely from said shank to a location beneath said movable jaw shoulder, the tongue of the latch plate next to said movable jaw engaging said movable jaw shoulder, said latch plates being tilttable conjointly by pressure of said shoulder on the latch plate tongue engaged thereby, by a force acting to separate said jaws, through a substantial angle into pinching engagement with said shank at an angle relative thereto greater than the angle of inclination of said shoulder end relative to said shank, to preserve contact between said plate and the side of said jaw shoulder farthest from said shank along a line perpendicular to the movable jaw and substantially directly beneath the center of its gripping part, thereby to restrain sliding of said movable jaw along said shank away from said fixed jaw, and a spring urging said latch plates toward said movable jaw into tilted attitude relative to said shank and against said movable jaw shoulder.

AUGUST C. ERTNER.
